UNITED STATES PATENT OFFICE.

JAMES H. HOOK, JOHN P. THOMPSON, AND MILO E. WOODBROW, OF CORTICANA, TEXAS.

ORGANIZED BUNCH-BUILDING MECHANISM FOR SPINNING OR TWISTING FRAMES.

Application filed September 9, 1922. Serial No. 587,081.

To all whom it may concern:

Be it known that we, JAMES H. HOOK, JOHN P. THOMPSON, and MILO E. WOODBROW, citizens of the United States, residing at 5 Corsicana, in the county of Navarro and State of Texas, have invented new and useful Improvements in Organized Bunch-Building Mechanism for Spinning or Twisting Frames, of which the following is a 10 specification.

The object of our said joint invention is the provision of a simple, durable and reliable bunch building mechanism designed more especially to build bunches on filling 15 bobbins for automatic looms and to operate in combination with a filling feeler with a view to assisting the feeler in reliable operation—i. e., in averting all of the yarn being unwound from the bobbins before the feeler 20 brings about changing of the bobbins in the shuttles and at the same time to limit the amount of yarn left on the bobbins when the change takes place, thereby avoiding the formation of thin places in cloth which 25 would naturally be the result were all the yarn unwound from the bobbins.

To the attainment of the foregoing the invention which is also advantageous because it reduces waste to a minimum, consists in 30 the improvement as hereinafter described and definitely claimed.

In the accompanying drawings, forming part of this specification:—

Figure 1 is a front view of an organized 35 mechanism constituting one embodiment of our invention.

Figure 2 is a detail broken elevation taken at right angles to and projected from Figure 1.

Figure 3 is a detail vertical section taken in the plane indicated by the line 3—3 of Figure 1, looking toward the right.

Figure 4 is a front view of a modified 45 organized mechanism constructed in accordance with our invention.

Figure 5 is a side view of said modified mechanism.

Similar numerals designate corresponding parts in Figures 1 to 3 to which reference will first be made.

Carried by the frame 1, an end of which is shown in Figure 2, are brackets 2, and journaled in the said brackets 2 is a rock shaft 3 on which is a lateral arm 4, disposed below a bracket arm 5 on the frame 1. Interposed between the said shaft arm 4 and

frame arm 5 and connected to the same is a retractile spring 6 which serves to yieldingly maintain the shaft 3 in and return the same to the position shown in Figures 1 and 2. Fixed to the shaft 3 and extending upwardly therefrom is a lever 7 which is preferably, though not necessarily, provided at 8 with an offset portion. Also fixed to and extending upwardly from the shaft 3 is a clutch lever 9 associated as shown in Figures 1 and 2 with a circumferentially grooved disk 10. The said disk 10 is mounted on a shaft 11, which is connected in the ordinary or any other approved manner with and is adapted to operate the traverse of the ring rail of the apparatus. This is common to all spinning frames and we have therefore deemed it unnecessary to illustrate the same. Fast on the shaft 11 is a cam 12, and arranged between the disk 10 and the cam 12 is a second cam 13. The cam 12 is retained on the shaft by a nut 14 or other appropriate means. The cam 13 is rotated through the medium of studs 15 which are fast to said cam 13 and extend through apertures 16 in the cam 12. When the cam 13 is moved through the medium of the lever 7 into a position close to the cam 12, said cam 13 is in such position that it will engage 70 the roller on the builder bar. When said cam 13 is in its normal inoperative position shown by dotted lines in Figure 2 it does not engage the roller on the builder bar.

At 17 is an arm on the spindle rail of the apparatus, and at 18 is a lateral sub-lever connected at 19 to the lever 7. Interposed between and connected to the arm 17 and the sub-lever 18 is a retractile spring 20. At 21 is an arm attached to the frame of the apparatus, and at 22 is a trip member of lever type, fulcrumed at 23 on the sub-lever 18 and having a lateral portion 24 opposed to the lower end of a rectilinearly movable rod 25.

At 30 is a sub-frame fixed in any approved manner to the frame 1. The rod 25 is guided in the upper and lower bars 31 and 32 of said sub-frame, and a spring 33 which surrounds the rod 25 is interposed between an abutment 34 on the rod and the upper bar 31 of the sub-frame. It will also be noticed by reference to Figure 1 that the rod 25 is provided with a series of beveled teeth 35; the series of teeth being employed so that the size of the bunch can be regulated. Mov- 105 able rectilinearly in the sub-frame 31 at

right angles to the line of movement of the rod 25 and adapted to engage the teeth of the rod 25 are upper and lower, spaced catches 40 and 41. The said catches 40 and 41 are pressed forwardly by springs 42 and their forward ends are opposed to the perimeters of the cams 12 and 13.

In the general operation of the mechanism described when the frame is stopped 10 for doffing purposes an attendant grasping the knob 60 on the rod 25 pulls the said rod upwardly and moves the lever 7 forwardly until the sub-frame or catch 18 engages with the arm or keeper 21. The movement of the 15 lever 7 and the attendant rocking of the shaft 3 forces the cam 13 against the cam 12, whereupon both cams will act against the roller of the builder arm 61 and thus bring about a short stroke or traverse of 20 ring rail and will cause a short bunch to be made at the bottom of each bobbin. As before indicated the size of the bunches is regulated by the number of notches employed in the rod 25.

25 The release of the cam 13 is effected when the point of the cam 12 contacts with the catch 40. At the said time the catch 40 is forced out of the notch in the rod 25 whereupon the rod will be forced downwardly by 30 the spring 33 and into engagement with the catch 41. The rod 25 then engages the lever 22 which disengages the lever 18 from the keeper 21. The cam 13 is forced backwardly by the action of the spring 6 so that the cam 35 12 only will be engaged with the roller on the builder arm. This assures full and regular strokes or traverse of ring rail, and the mechanism is not further manipulated until the frame is ready to doff again.

40 It will be gathered from the foregoing that bobbins on which bunches are built by our improvement are especially designed for use in feeler looms; also, that our novel mechanism is simple and compact in construction and embodies no delicate parts 45 such as are likely to get out of order after a short period of use.

In the modification shown in Figures 4 and 5, cams 12^a and 13^a on a shaft 11^a are 50 employed; the cams and shafts being similar to the cams 12 and 13 and the shaft 11 of the embodiment shown in Figures 1-3. In common with the mechanism of Figures 1-3, the modified construction also comprises a 55 rock shaft 3, a circumferentially-grooved disk 10, a lever 9 and a body 10 and a spring 6.

In the modification and in combination with the elements enumerated we employ a 60 trip 22^a and trip lever 22^b, a builder arm 60 carrying an anti-friction roller opposed to the cams 12^a and 13^a, a pick gear 70, and a let-off pawl 71, the pick gear, let-off pawl and trip lever being designed to serve the 65 same purpose as the rod 25 of Figures 1-3

and the appurtenances thereof. In accordance with usual practice the pick gear is attached to the builder arm 60, and said pick gear is moved vertically by the cams acting against the roller on the builder arm. Manifestly as the pick gear moves upwardly the let-off pawl 71 retains its position as one of its ends is heavier than the other. The end of said pawl 71 remote from the weighted end is equipped with a let-off dog 71^a which 70 engages the teeth of the pick gear. Therefore, incident to downward movement of the builder arm, the pick gear is turned through a part of a revolution, or step by step until a pin 70^a on the pick gear 80 engages the trip lever and disengages the loose cam 13^a from the cam 12^a whereupon said cam 13^a will be out of alignment with the roller on the builder arm and the worm cam 12^a will control the movement of the 85 builder arm until the frame is ready to doff again. In the modified construction the bunch size is regulated by the positioning of the pin 70^a in the pick gear; said pick gear being provided as shown with a plurality of 90 apertures in any one of which the pin can be placed as conditions require.

We also show in Figures 4 and 5, a run-off gear 80, the usual shaft 81 carrying the let-off pawl and the worm 82 meshed with the gear 80 and the usual builder chain 83 connected with the gear 80 and passed about a sheave 84, mounted upon the builder or spinning frame head 85.

Having described our invention, what we 100 claim and desire to secure by Letters-Patent, is:—

1. In an organized bunch building mechanism, the combination of a rotary member for connection with the transverse of a ring rail, movable builder means, cams in side by side relation on the rotary member and opposed to and adapted to control said movable builder means, one of the said cams being fast to the rotary member and the other 105 cam rotatable with and movable laterally relative to the fast cam, means to move the laterally movable cam relative to the fast cam and into position to engage the builder means, and automatic means to move the laterally movable cam out of position to engage the builder means; the said automatic means including a toothed or notched rod, a spring 110 to move the same, a trip operable by the rod when released, and catches to hold the rod against movement by the spring, said catches being cam-controlled.

2. In an organized bunch building mechanism, the combination of a rotary member for connection with the transverse of a ring rail, movable builder means, cams in side by side relation on the rotary member and opposed to and adapted to control said movable builder means, one of the said cams being fast to the rotary member and the other 115 120 125 130

- cam rotatable with and movable laterally relative to the fast cam, means to move the laterally movable cam relative to the fast cam and into position to engage the builder means, and automatic means to move the laterally movable cam out of position to engage the builder means; the said automatic means including a toothed or notched rod, a spring to move the same, a trip operable by the rod when released, a rock shaft with a lever and an arm, the latter to move the loose cam, and catches to hold the rod against movement by the spring, said catches being cam-controlled.
- 15 3. In an organized bunch building mechanism, the combination of a rotary member for connection with the transverse of a ring rail, movable builder means, cams in side by side relation on the rotary member and opposed to and adapted to control said mova-
- ble builder means, one of the said cams being fast to the rotary member and the other cam rotatable with and movable laterally relative to the fast cam, means to so move the laterally movable cam, and automatic means to move the laterally movable cam relative to the fast cam, the first of said means including a spring-actuated rock shaft with an arm in connection with the laterally movable cam and with a lever, and the automatic means including a spring-pressed toothed rod, a trip operable by said rod when the same is released, and cam controlled catches adapted to normally hold the rod against movement under the action of its spring.
- 20 In testimony whereof we affix our signatures.

JAMES H. HOOK.
JOHN P. THOMPSON.
MILLO E. WOODROW.
